No. 36,711.

Patented December 29, 1903.

UNITED STATES PATENT OFFICE.

MARTINUS VAN GELDER, OF PHILADELPHIA, PENNSYLVANIA.

DESIGN FOR A CUP.

SPECIFICATION forming part of Design No. 36,711, dated December 29, 1903.

Application filed October 22, 1903. Serial No. 178,156. Term of patent 14 years.

To all whom it may concern:

Be it known that I, MARTINUS VAN GELDER, a subject of the Queen of the Netherlands, residing at Philadelphia, in the county of Philadelphia and State of Pennsylvania, have invented a new, original, and ornamental Design for Cups, of which the following is a specification, reference being had to the accompanying drawing, forming part thereof.

The drawing shows in perspective my new, 10 original, and ornamental design for cups.

What I claim is—

The ornamental design for a cup, as shown.

MARTINUS VAN GELDER.
